THERMOSTATIC REGULATOR

Nathan Morris, Silver Spring, Md., assignor to
American Instrument Company, Silver Spring,
Md., a partnership composed of William H.
Reynolds and Leopold Freeman

Application May 5, 1944, Serial No. 534,315

7 Claims. (Cl. 200—138)

1

My invention relates broadly to thermoregulators and more particularly to a construction of precision adjustment means for thermoregulators.

One of the objects of my invention is to provide a construction of thermoregulator having precision adjustment means for accurately setting the thermoregulator for controlling an electric circuit at an exact predetermined temperature.

Another object of my invention is to provide a construction of spring control device for selectively fixing the position of the adjustable head of a thermoregulator for control of an electric circuit at a predetermined temperature.

Other and further objects of my invention reside in the construction of precision adjustment means for thermoregulators as set forth more fully in the specification hereinafter following by reference to the accompanying drawings, in which:

Figure 1 is a side elevational view of the thermoregulator of my invention showing the orientatable head carried thereby; Fig. 2 is a top plan view of the orientatable head in position on the thermoregulator; Fig. 3 is an enlarged side elevational view of the orientatable head with parts broken away and illustrated in longitudinal section for showing the coaction of the parts; Fig. 4 is a transverse sectional view taken on line 4—4 of Fig. 3; Fig. 5 is a fragmentary sectional view taken on line 5—5 of Fig. 4 and showing the securing means for the orientatable head in released position so that the orientatable head may be angularly shifted to a selected position; Fig. 6 is a cross sectional view similar to the view illustrated in Fig. 5 but showing the securing means for the orientatable head set in position for maintaining the orientatable head in a predetermined selected position; and Fig. 7 is a perspective view of the resilient key that I employ in the structure of my invention.

My invention is directed to a construction of thermoregulator in which a bimetallic spiral element is employed to produce an axial displacement of a contact member movable between a pair of selectively adjustable contacts. The selectively adjustable contacts are carried by a casing or head of insulation material which is supported in a frame and capable of angular adjustment thereof. The frame also provides mounting means for the spiral thermosensitive member that controls the displacement of the contact member between the pair of adjustable contacts. The casing which is supported by the frame has an annular groove therein into which

2

a flat spring member fastened to the frame structure extends as a key or tongue. The spring member secured in the frame extends substantially tangent to the interior surface of the annular groove in the casing and forms an adjustable key which may be rendered effective or ineffective to secure the casing in fixed position or allow the casing to be angularly shifted to a selected position and set therein so that the movable contact member may meet and establish a connection with either of the adjustable contact members at a predetermined temperature setting. An index device is carried by the frame and a calibrated scale is carried by the casing coacting with the index device whereby the proper angular settings for the casing may be determined.

Referring to the drawings in detail, reference character 1 designates the frame of the thermoregulator having a tubular projection 2 thereon which supports the tubular member 3 through which the actuating rod 4 extends to the end of the spirally arranged bimetal thermosensitive element 5. The end of the actuating rod 4 connects to the bimetal thermosensitive element 5 at the end position 6. The actuating rod 4 projects through the frame of the thermoregulator and carries a bushing 7 having a pin 8 thereon which forms a retaining means for the end of the spiral safety spring 9 which is wrapped around the actuating rod 4 and terminates in a radial extension represented at 10 substantially parallel to the radial extension 11 at the opposite end thereof. The two extreme ends 10 and 11 of the tension spring 9 terminate on opposite sides of the member 12 which is carried by the insulated disc 14 that is floatingly carried by actuating rod 4. That is, actuating rod 4 passes loosely through insulated disc 14 so that insulated disc 14 is indirectly operated by actuating rod 4 through the inner position of tension spring 9. The insulated disc 14 is cut off substantially on a chord adjacent one edge thereof and serves as a support for the contact carrier strip 15. Contact carrier strip 15 carries contacts 16 and 17 on opposite faces of the end thereof which may be displaced between adjustable contacts 18 and 19. Adjustable contacts 18 and 19 are carried by adjusting screws 20 and 21 which are adjustable from the exterior of the angularly adjustable casing 22 of molded or plastic material. Knurled finger grips 20a and 21a are provided on the exterior ends of adjusting screws 20 and 21 to permit adjustment of the spacial relation of the adjustable contacts 18 and 19 to a precise spacial relation. Electrical

connection is established with the screw threads 18a and 19a of the adjustable contacts 18 and 19 by means of brush members 23 and 24 connected with binding posts 25 and 26 carried by casing 22. Casing 22 also carries a binding post 27 which is connected through the spiral hair spring 28 arranged interiorly of casing 22 to the contact carrying member 15, thereby establishing electrical connection with the movable contacts 18 and 17.

The frame of the thermoregulator carries an index pointer 29 which coacts with the calibrated scale 30 carried by the casing 22. The casing 22 is angularly shiftable within the socket-like support in frame 1 formed by the projecting cylindrical portion 31 of frame 1. It will be seen that the casing 22 fits into the projecting cylindrical portion 31 of frame 1 and is rotatable therein. The casing 22 is provided with an annular groove 22a molded therein in a position which is substantially central of a skirt portion 32 adjacent the base of the casing. The annular groove 22a is molded in the casing 22 and serves as an interlock between the orientatable casing and the frame 1 through the interposition of the key member 33. The member 33 is an L-shaped flat resilient strip having a width somewhat less than the width of the annular groove 22a and having the end portion thereof extending through a vertical slot 34 formed in the projecting cylindrical portion 31 of frame 1. The strip 33 is formed from resilient material and normally tends to extend approximately tangent to the interior surface of the annular groove 22a. Resilient strip 33 normally has the opposite end 33a thereof resting in contact with the interior surface of the wall of the projecting cylindrical portion 31 of frame 1 in which position the casing 22 is free to be oriented for moving the contacts 18 and 19 into predetermined spacial relation with the contacts 16 and 17 as determined by the calibrated scale 30 with reference to the index pointer 29.

When the casing 22 has been oriented to a selected position, the adjusting screw 35 is advanced through the screw threaded aperture 36 in the projecting cylindrical portion 31 of the frame 1 with the end 37 of the screw bearing against the flat surface of strip 24. Screw 35 is provided with a shoulder 38 which abuts with the outside wall of the projecting cylindrical portion 31 of the frame for restricting or limiting the advancement of the screw beyond a safe limit. Screw 35 is provided with a knurled finger grip 39 for moving screw 35 into locking position. As the end 37 of screw 35 bears against resilient strip 33, the strip 33 is displaced against the interior face of annular groove 22a frictionally wiping the annular face of groove 22a and locking casing 22 in a set position. Thus by distributing the pressure from the end of the set screw through the interposition of strip 33 it is possible to obtain an interlock of great precision. Pressure of screw 35 is thus obviously distributed over a relatively large area and mutilation and wear of the inner groove wall is minimized. It is thus possible to set the position of the contacts 18 and 19 with respect to the path of movement of contacts 16 and 17 for securing operation of the thermoregulator at an exact predetermined temperature.

The casing 22 is formed from molded plastic material which is capable of providing mounting means for the several binding posts and capable of retaining the annular groove 22 in the casing under conditions of long continued use.

While I have described my invention in one of its preferred embodiments, I realize that

changes may be made in the exact arrangement of parts of the structure and I desire that it be understood that no limitations upon my invention are intended other than may be imposed by the scope of the appended claims.

What I claim as new and desire to secure by Letters Patent of the United States is as follows:

1. A thermoregulator comprising in combination a supporting frame, a thermosensitive element supported by said frame, an angularly adjustable casing supported in said frame, contact members supported by said adjustable casing, a contact device disposed within said adjustable casing and controlled by said thermosensitive element for operation with respect to the aforesaid contact members, said casing having an annular groove adjacent the base thereof, a flat spring member carried by said frame and extending into said groove and an adjusting screw extending through said frame and engaging said flat spring for forcing said flat spring member into frictional locking engagement with the groove in said adjustable casing for maintaining said casing in a predetermined position in said frame.

2. A thermoregulator comprising in combination a supporting frame, a thermosensitive element supported by said frame, an angularly adjustable casing supported in said frame, contact members supported by said adjustable casing, a contact device disposed within said adjustable casing and controlled by said thermosensitive element for operation with respect to the aforesaid contact members, said casing having an annular groove adjacent the base thereof, a flat strip-like member extending through a slot in said frame member and into the annular groove adjacent the base of said casing and forming an interlock between said casing and said frame and means carried by said frame for rendering said strip-like member effective or ineffective to maintain said casing in a predetermined position with respect to said frame.

3. A thermoregulator comprising in combination a supporting frame, a thermosensitive element supported by said frame, an angularly adjustable casing supported in said frame, contact members supported by said adjustable casing, a contact device disposed within said adjustable casing and controlled by said thermosensitive element for operation with respect to the aforesaid contact members, said casing having an annular groove adjacent the base thereof, an L shaped flat strip member having one end thereof secured in said frame and the other end thereof projecting into the annular groove adjacent the base of said casing and substantially tangential to the wall of said annular groove and means carried by said frame for variably controlling the frictional engagement of said flat strip member with the annular groove of said casing.

4. A thermoregulator comprising in combination a supporting frame, a thermosensitive element supported by said frame, an angularly adjustable casing supported in said frame, contact members supported by said adjustable casing, a contact device disposed within said adjustable casing and controlled by said thermosensitive element for operation with respect to the aforesaid contact members, said casing having an annular groove adjacent the base thereof, a resilient strip extending between said frame and the annular groove in said casing and a screw device carried by said frame and engageable with said strip for

frictionally interlocking said casing with said frame in a predetermined position.

5. A thermoregulator comprising in combination a supporting frame, a thermosensitive element supported by said frame, an angularly adjustable casing supported in said frame, contact members supported by said adjustable casing, a contact device disposed within said adjustable casing and controlled by said thermosensitive element for operation with respect to the aforesaid contact members, said casing having an annular groove adjacent the base thereof, a spring member positively secured to said frame and frictionally wiping the interior wall of the annular groove adjacent the base of said casing and an adjustable screw extending through said frame and engaging said spring member for frictionally interlocking said casing in a predetermined position in said frame.

6. A thermoregulator comprising in combination a supporting frame, a thermosensitive element supported by said frame, an orientatable casing supported in said frame, a calibrated scale carried by said casing, an index member carried by said frame in coaxing relation to said calibrated scale, contact members supported by said orientatable casing, a contact device disposed within said adjustable casing and controlled by said thermosensitive element for operation with respect to the aforesaid contact members, said casing having an annular groove adjacent the base thereof, a key member secured to said frame and extending substantially tangential into said

annular groove and a screw device carried by said frame and adjustable with respect to said key member for frictionally interlocking said casing with respect to said frame at a predetermined position.

5. A thermoregulator comprising in combination a supporting frame, a thermosensitive element supported by said frame, an angularly adjustable casing supported in said frame, contact members supported by said adjustable casing, a contact device disposed within said adjustable casing and controlled by said thermosensitive element for operation with respect to the aforesaid contact members, said casing having an annular groove adjacent the base thereof, a spring member carried by said frame and extending into said annular groove, an adjusting screw extending through said frame and engageable with said spring member and an annular shoulder on said adjusting screw arranged to abut with the external surface of said frame for limiting the extent of projection of said adjusting screw into said frame and restricting the movement of said spring member into said annular groove.
